UNITED STATES PATENT OFFICE.

HORMIDAS S. MIRANDETTE, OF SPENCER, MASSACHUSETTS.

SOLE-CUTTER AND NUMBERING-MACHINE.

1,033,764.

Specification of Letters Patent. Patented July 23, 1912.

Application filed February 1, 1911. Serial No. 605,953.

To all whom it may concern:

Be it known that I, HORMIDAS S. MIRANDETTE, a citizen of the United States of America, residing at Spencer, in the county 5 of Worcester and State of Massachusetts, have invented certain new and useful Improvements in Sole-Cutters and Numbering-Machines, of which the following is a specification.

10 This invention relates to shoe machinery and particularly to a combined sole cutting and numbering machine.

An object of this invention is to provide means for cutting the edges of the soles at 15 four different locations, viz., at the toe curve of the sole on the inside of the ball line O and at the front portion of the heel on each side in order that the edge portions of the soles may be turned up without curling, said 20 sole edges being cut half way through.

A further object of this invention is to provide novel means for stamping the size, by number, on the said soles and in this connection a novel system of numbering is 25 employed and made effective by the position of the numbers with relation to the edges of the sole or heel; the invention further contemplating the provision of novel means for permitting movement of the sole numbering 30 element and means for retaining the said element at different positions of adjustment.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this specification 40 wherein like characters denote corresponding parts in the several views, and in which—

Figure 1 illustrates a view in front elevation of a machine embodying the invention; 45 Fig. 2 illustrates a side elevation thereof; Fig. 3 illustrates a top plan view; Fig. 4 illustrates a view similar to Fig. 2 except that a portion of the machine is omitted and the cutting head is in its lowermost position; 50 Fig. 5 illustrates an enlarged detail view of the work rest or table; Fig. 6 illustrates a detail view of a fragment of said table, partly in section showing the means for retaining the numbering mechanism at different 55 positions of adjustment; Fig. 7 illustrates a perspective view of one of the

knives; cutting the slit in the edge portion of the sole; Fig. 8 illustrates a perspective view of an edge cutter designed to operate at the toe end of the sole; Fig. 9 illustrates a plan view of the sole after being subjected to the action of the machine; Fig. 10 illustrates a detail view of a fragment of the sole showing the heel portion thereof numbered to denote a size different from that indicated in Fig. 9; and Fig. 11 illustrates an edge view of a portion of the sole shown in Fig. 10, with the edge cut half-way through.

In these drawings 12 denotes a base having a standard 13 rising therefrom and terminating in a bearing 14 for the reciprocating rod 15 which extends downwardly through the base and is designed to be moved in any suitable manner for the purpose of carrying the cutter head (to be presently explained). The base 12 is provided with a bed plate 16 containing a work rest 17 which work rest is provided with a series of plates 18 termed "holding plates" or lugs, which are provided for the purpose of holding the edges of the soles 19 which may be applied to the work rest. It is shown in Fig. 5 that the holding plates or lugs 18 having slots 20 which permit the movement of the holding plates relative to the binding screws 21, 25 by which they are held on the work rest, therefore the position of said plates may be changed to suit the particular configuration of the sole being held. The standard 13 has a guide 22 on its inner edge which is 30 engaged by a heel 24 of the cutter head 25, the said cutter head being provided with an aperture 26 for the reception of the rod 15, and said head is further provided with a binding screw 27 which is designed to engage the rod 15 for clamping the cutter head thereto so that the reciprocal motion of the rod is communicated to the head and the 35 said head is carried thereby.

The cutter head has a plate 28 secured to it by the bolts 29 which bolts extend through slots 30 in the cutter head and through slots 31 in the plate 28 thereby permitting the adjustment of the plate 28 transversely as well as rearwardly and forwardly of the cutter 40 head. The plate 28 has the edge cutting knives 32 secured to its edge by means of the screws 33, the said knives 32 being provided with slots 34 which permit the adjustment of the knives under the influence 45 of the screws 35 which are threaded in the lugs 36 on the plate 28. As heretofore

stated, the knives 32 are three in number and are designed to operate on the soles for cutting the same on each side of the sole in front of the heel, on the inside of the ball line. The knife 37 which is provided to cut the sole at the toe end thereof is different in contour from the knife 32 and has two cutting edges 38 and 39 at right angles to each other. The knife 37 is provided with the slot 40 in order that it may be adjusted 10 on the screw 41 under the influence of the said screw 35.

A plunger 42 extends through the cutter head and through the plate 28 and is designed to coact with the numbering mechanism to be presently explained. The plunger 42 is secured to the head by means of a set screw 43 extending through the said plunger and anchored in the edge of the head.

Under the influence of the rod 15, the head 25 may be moved from the position shown in Fig. 2 to the position shown in Fig. 4 in which latter position the knives and plunger are coacting with the work rest 20 and numbering mechanism to operate on the sole 44 in which position of the parts the sole is provided with the slots or cuts 45, 46, 47 and 48 as well as the numeral 5 shown in Fig. 9 of the drawing.

For the purpose of numbering the soles, the work rest is provided with a slot forming a seat for the die bar 49 which die bar has a series of numbering dies 50 which may be brought to position under the plunger 42 for the purpose of pressing the sole into contact with the number on the die in order that the size of the sole may be impressed thereon. In this connection a system of 30 numbering is utilized which has been found advantageous and to that end the numbers have been put on the dies in such a way as to indicate whether the numeral applied to the sole denotes a full size or a full size and a half size of the number impressed thereon. To that end, the said numbers have been placed on the die so that they will stand vertically with relation to the edges of the sole or diagonally with relation to said 40 edges. The former position of the member will indicate that the size of the sole corresponds to the number applied thereto whereas where the number is arranged at an angle or diagonally of the sole it will indicate a half size of an additional number, for instance in Figs. 9 and 10, Fig. 9 is marked to denote that the size is number 5 whereas in Fig. 10, the numeral indicates that the sole is size five and one-half.

The bar 49 is provided with seats or recesses similar to the recess 51 shown in Fig. 6 and the said recess is designed to receive a latch 52 which extends through an aperture 53 in the work rest. The latch is pressed inwardly by means of the spring 54 so that

its inner end may be seated in the recess 51 of the bar, thus holding the bar against movement until the latch is manipulated for releasing the bar when the said bar may be set to position a die of the desired number under the plunger. By this means, the numbering mechanism may be associated with a cutting mechanism and the said numbering mechanism may be made interchangeable or adjustable so that the proper numeral 75 may be applied to the sole.

I claim—

1. In a sole cutting and numbering machine, a base, a bed-plate supported by said base, a work-rest on said bed-plate, said work-rest having a channel, a numbering die-bar adjustably mounted in said channel, a standard having a bearing in the upper portion thereof, a rod adapted to reciprocate in said bearing, a cutter-head carried by said rod, said cutter-head carrying cutting knives, a plunger carried by said cutter-head, said plunger adapted to coact with the dies of the numbering die-bar.

2. In a sole cutting and numbering machine, a base, a bed-plate supported by said base, a work-rest supported by said bed-plate, and having a channel therein, said work-rest adapted to support the material under treatment, a numbering die-bar adjustable in said channel, means for holding the numbering die-bar in its positions of adjustment, a standard integral with said bed-plate, said standard having a bearing in the upper portion thereof, a rod adapted 100 to reciprocate in said bearing, a cutter-head secured to said rod, knives secured to said cutter-head, a plunger carried by said cutter-head, said plunger adapted to coact with the dies of the numbering die-bar.

3. The combination with a sole cutting machine, having a work-rest and a channel in said work-rest, a movable cutter-head, a numbering mechanism comprising a numbering die-bar having dies in the surface 110 thereof, said numbering die-bar being adjustable in said channel, a latch member for holding said numbering die-bar in its positions of adjustment, a plunger carried by and movable with said cutter-head, and said plunger adapted to coact with said dies on the numbering die-bar.

4. In a sole cutting and numbering machine, a base, a bed-plate supported by said base, a work-rest mounted on said bed-plate, a standard having a bearing in one end thereof supported by said bed-plate, a rod carrying a cutter-head, adapted to reciprocate within said bearing, a guide on said support, said guide adapted to engage the heel of said cutter-head, a plunger on said cutter-head, said plunger adapted to move therewith, a numbering die-bar supported by the work-rest, means for reciprocating the said cutter-head, and the said

125
130

plunger adapted to coact with the dies of the numbering die-bar.

5. In a sole cutting and numbering machine, a base, a work-rest supported there-by, said work-rest having a channel, a num-bering die-bar adjustable in said channel, means for holding the numbering die-bar in its positions of adjustment, a cutter-head, a knife having cutting edges at an angle to 10 each other carried thereby, said knife

adapted to cut the toe portion of a sole, knives with straight edges for cutting the sole at the sides thereof, and means for re-ciprocating said cutter-head.

In testimony whereof, I affix my signa-ture in the presence of two witnesses.

HORMIDAS S. MIRANDETTE.
